UNITED STATES PATENT OFFICE

EDWIN WALKER TILTON, OF HAVERHILL, MASSACHUSETTS, ASSIGNOR TO LEWIS
LESTER COWAN

BALLET SLIPPER AND PROCESS OF MAKING SAME

Application filed January 7, 1925. Serial No. 1,093.

This invention relates to improvements in dancing slippers or shoes and one of its leading objects is to provide a non-collapsible toe which will not be bulky in appearance and which will provide firm support for the dancer, without binding or cramping the foot of the wearer.

Another object of the invention is the provision of a dancing or ballet slipper or shoe having a toe box located between the upper leather and a reinforcing fabric, the forward marginal edge portions of which are secured between the insole and the base of the toe box.

Another object of the invention is the provision of a process for making shoes of this type, by a special turning operation, used in connection with the particular toe box and mounting.

With the above and other objects in view the invention consists in certain new and useful constructions, combinations and arrangements of parts, clearly described in the following specification and fully illustrated in the accompanying drawings, in which:—

Fig. 1 is a side elevation, of a completed slipper.

Fig. 2 is a top plan view thereof.

Fig. 3 is a bottom plan view of a partly completed slipper, showing the upper leather for covering the toe box partly secured in position.

Fig. 4 is a detail sectional view of the toe of the slipper.

Fig. 5 is a detail transverse sectional view through the toe portion of the slipper.

Fig. 6 is a partial perspective view of the toe portion of the slipper showing the marginal edges of the toe portion of the upper folded back from the insole.

Fig. 7 is another transverse sectional view taken through the rear portion of the sole.

Fig. 8 is a bottom plan view of the toe box.

Fig. 9 is a longitudinal section thereof.

Referring to the accompanying drawings illustrating the practical construction of my improved shoe, 5 designates an upper of soft, flexible leather, and 6 the outer sole. The outer sole is made shorter and narrower than the bottom of the upper, and is constructed

without the usual shoe heel, since the heels of the ordinary type are not employed in ballet slippers.

The outer sole is provided with a marginal shoulder 6^a on its upper side, and with a series of small transverse holes formed by means of an awl for receiving the stitching thread. Inwardly of the shoulder a sloping cut 6^c is formed, which is approximately parallel to the shoulder, and which provides an overlying flexible lip or flange.

The forward portion of the upper 5 is provided with a reinforce of canvas 8, which is sewed with the toe cap 5' of the upper to the body of the upper, by slanting seams, indicated at 9, one located on each side of the forward half of the upper.

The upper 5 is provided with the usual cloth or fabric lining 5^a, sewed thereto, and the lower marginal edge portions of the rear part of the upper leather and the cloth lining are sewed to the outer sole, by stitches 13 being received in the cut 6^c and through the shoulder 6^a, as shown in Fig. 7. The toe portion of the lining 5^a and the canvas reinforce 8 are stitched to outer sole by the stitches 13 passing through the shoulder 6^a and into the channel or cut 6^c, leaving the top cap 5' unattached. The upper 5 and the cloth lining 5^a are attached to the outer sole by turning the upper inside out, and after the cloth is completely sewed and the upper is partly attached by a sewing operation through the cut 6^c, and the shoulder 6^a, the construction of the toe is subsequently completed, by turning the shoe with its normal inside in and inserting the inner sole 7.

The rigid leather box toe 10 then is disposed between the toe cap 5' and the reinforce 8, after which operation the base flange of the toe box and the outer edge of the reinforce and lining are tacked by tacks 10' to the inner sole 7 while the shoe is held on the iron last. Then the toe cap of the upper leather is worked into a series of tucks and stitched directly to the outer sole.

Since the toe cap 5' is sewed to the outer sole with the shoe turned with its normal inside inwardly, it is desirable, among other reasons, to sew the toe cap to the outer sole

in such a manner that the two portions, namely, the body and the toe cap 5' will appear to be sewed by the same method.

To accomplish this purpose I provide bottom of the outer sole 6, with the slanting grooves 11 and 12, disposed at angular relation to each other. The depth of these grooves is sufficient to conceal the stitches 13' when the lips thereof, as shown in Fig. 4, are forced in their normal position, after completing the stitching operation, which will now be fully explained.

As previously described, the toe cap 5' is worked into a series of tucks between the outer sole and the box 10, after which the needles are projected through the grooves 11 and 12, shoulder 6^a, and through the lower edge of the toe cap. The stitches are then drawn tight so that the stitching thread will not project from the surface of the outer sole, and will in fact be wholly concealed by the lips of the grooves 11 and 12.

In this manner, the toe cap is sewed to the outer sole in a similar manner as if the box 10 were removed and the sewing operation performed while the shoe is turned with its outer side in. Moreover, the box toe is securely fastened to the outer sole and incorporated in the progressive construction of the shoe, whereby it is unadapted to become loosened.

An advantage of the invention is that a stiffened box toe 10, formed from leather or other suitable material, may be inserted between the reinforced lining and the upper leather, and secured in position after the upper is made and a portion of it is sewed to the outer sole while the shoe is turned, and without the unsatisfactory necessity of forcing the box toe into position after the entire upper has been secured to the outer sole.

A formed or a moulded box toe of leather or other material may thus be used, to effect great durability of the toe of the slipper retaining its original shape.

As usual, the forward portion of the shoe is disposed at an oblique angle to the rear portion thereof. The usual tightening cord is arranged around the marginal portion of the mouth of the shoe, and the usual eyelets may be provided for lacing the shoe to the foot of the wearer.

It is quite apparent that an important feature of the invention is the method of sewing the lower edge of the toe cap 5' to the outer sole 6.

The grooves 11 and 12, as shown, merely represent a convenient means of permitting a worker to protrude the point of the needle, bearing the thread 13', through the outer sole which generally is of tough leather. Moreover, the directions in which the grooves extend enable the worker to quickly and conveniently pass the needle and thread successively through the outer sole directly into and

through the lower edge of the toe cap, and vice versa. Usually two threaded needles are simultaneously projected, in opposite directions, through the materials.

During the sewing operations the materials of the slipper, except the box toe 10, are pliable. When the slipper is completely sewed the edges of the upper may be trimmed closely to the stitches whereby, although the toe cap is sewed when the normal outer side of the shoe is turned out, the completed slipper appears to have been sewed completely while the normal outer side is turned in.

Another important advantage of the method is that the box toe 10 is securely tacked, or otherwise fastened to the outer sole, while the toe cap is capable of being folded rearwardly of the slipper to permit the worker to have free and unobstructed access to the box toe. Otherwise, where the toe cap is sewed to the outer sole, and after which the box toe is inserted, the difficulty of a worker in securing the box toe in position has been such that after the slipper is in use a short period the box becomes loosened from its point of anchorage. And if the box toe is constructed from laminations of canvas, afterward treated to form a stiff and inflexible box toe, the perspiration of the feet of the wearer soon absorbs into the previously treated canvas, or the heat of the body disadvantageously effects the treated canvas, whereby the box toe becomes sufficiently weakened as to be incapable of sustaining the weight of the wearer. Whereas, a box toe formed of material having the required natural strength or stiffness may be securely incorporated in the slipper by utilization of the herein described and claimed invention.

It is, therefore, apparent that I have invented a highly desirable device and method of accomplishing the intended purposes.

While I have chosen to illustrate the forms and constructions of my invention by the herein drawings and explanations of the same, it is understood that the invention resides in the combination, arrangement of the parts and in the details of the construction, as hereinafter claimed. It is further understood that changes in the precise embodiment of the invention, as disclosed herein, can be made within the scope of what is claimed without departing from the spirit of the invention, as other expedients may readily suggest themselves to the art.

What I claim as new and desire to secure by Letters Patent is:

1. A method of making a ballet slipper comprising an upper having a toe cap and an outer sole, said method comprising first sewing the upper, except the toe cap, to the outer sole, with the upper turned inside out, then turning said upper, then sewing the toe cap to the outer sole by drawing the thread successively through a central portion of the

outer sole and through the lower edge of said toe cap.

2. A method of making a ballet slipper, having a toe cap, comprising first sewing the upper, except the toe cap, to the outer sole, with the upper turned inside out, then turning said upper, then sewing the toe cap to the outer sole by drawing the thread successively through the outer sole and through the lower edge of said toe cap.

3. A method of making a ballet slipper comprising an upper, having a toe cap, an outer sole having a recess therein, an inner sole, a cloth lining and a box toe having canvas reinforce, said method comprising first sewing the upper and the cloth lining, except the toe cap, to the outer sole, with the upper turned inside out, then turning said upper, then securing the inner sole in said slipper, then securing the box toe and the reinforce to the front end of the inner sole, then tucking the edge of said toe cap over said box and said reinforce and then sewing through said recess to secure the edge of said toe cap to said outer sole.

4. A method of making a ballet slipper, having a toe cap, comprising first sewing the upper, except the toe cap, to the outer sole, with the upper turned inside out, then turning said upper, then securing a box toe to the inner sole, then tucking the edge of said toe cap over said box toe and then sewing the edge of said toe cap to said outer sole, by drawing the thread through the lower edge of said upper and through the central portion of said outer sole, substantially as described.

5. A method of making a ballet slipper comprising forming a cut in the marginal portion of the upper side of the outer sole having a groove therein, said cut slanting downwardly and outwardly, then, while the normal inside of the upper is turned out, sewing, through said cut, the lower edge of the rear portion of the upper of said slipper to said outer sole, said upper having a toe cap, then turning said upper and inserting an inner sole in said slipper, then securing a leather box toe having a flat front to the lower side of said inner sole at the front thereof, then covering said box toe with the toe cap of said upper, and then, through said groove, sewing said toe cap to the outer sole.

6. A method of making a shoe, which includes forming a groove in the outer sole, then, while the normal inside of the upper is turned out, sewing the lower edge of the rear portion of the upper and the complete canvas lining of said shoe, except the toe cap, of the upper to said outer sole, then turning the normal outside of said shoe out and inserting an inner sole in the slipper, then securing a box toe in said shoe to the lower side of said inner sole at the front thereof, then covering said box toe with the toe cap of said

upper, and then sewing said toe cap to the outer sole through said groove.

7. A method of making a ballet slipper comprising forming a groove in the front portion of the outer sole, then, with the normal inside of the upper, having a toe cap, turned out, sewing the rear portion of said upper to said outer sole, then inserting a box toe adjacent the front portion of said outer sole, then covering the box toe with the toe cap of said upper and sewing the edge of said toe cap to said outer sole by inserting thread through said groove and through the edge of said toe cap.

8. A method of making a ballet slipper comprising forming a groove in said outer sole, then with the normal inside of the upper turned out, sewing a portion of said upper, having a toe cap, to said outer sole, then inserting an inner sole in said slipper, then securing a box toe adjacent to front portion of said inner sole, then covering the box toe with the toe cap of said upper and sewing the edge of said toe cap to said outer sole by drawing thread through said groove and through the edge of said toe cap.

Signed by me at Haverhill, Mass.
